GEORGE E. BURT, OF HARVARD, MASSACHUSETTS.

Letters Patent No. 66,074, dated June 25, 1867; antedated December 25, 1866.

IMPROVEMENT IN HAY-SPREADERS.

The Schedule referred to in these Letters Patent and making part of the same.

TO ALL WHOM IT MAY CONCERN:

Be it known that I, GEORGE E. BURT, of Harvard, in the county of Worcester, in the State of Massachusetts, have invented new and useful Improvements in Hay-Tedders; and I do hereby declare that the following is a full and exact description thereof, reference being had to the accompanying drawings, making a part of this specification, in which—

Figure 1 is a bird's-eye view.

Figure 2 is a side elevation.

Figure 3 is a transverse section of the end of the cylinder C nearest the pinion P.

Figure 4 is a longitudinal section of one end of the cylinder C nearest the pinion P, showing the same parts as those shown in fig. 3.

Figures 5 and 6 are transverse and longitudinal sections taken in the middle part of the cylinder C, to show the connections and operation of the forks f f.

Figure 7 is a side elevation with the wheels removed so as to show the manner in which the rake R balances the tedder.

Figure 8 is a diagram showing the relative position of the forks and connecting arms, when the shank of the fork is pivoted to the connecting arm.

Figure 9 is a diagram showing the relative position of the forks and connecting arms, when the coil of the fork is pivoted to the connecting arm.

Figure 10 is a diagram showing the same connections as fig. 8; but so constructed that the forks may be readily removed and repaired when injured.

Figure 11 is a diagram showing the same connections as fig. 9; but also so constructed that the forks may be readily removed and repaired.

Figure 12 is a skeleton of the rotating heads, showing the eccentrically placed shaft L, and the shafts a a by which the forks are connected with the heads, and upon which they swing.

Figure 13 is an end view of the rotating heads, showing the position of the eccentrically placed shaft L.

The same letters represent like parts in all the figures.

It is well known that hay-tedders constructed with rotating or revolving forks get clogged and choked with hay, when in operation, especially when open or barred cylinders are used, as the hay is liable to be drawn on to them by the rotary motion of the forks.

The nature of my invention consists in giving a positive accelerated motion to the forks while they act on the hay, causing them to toss the hay before them and clear themselves entirely from it, thus avoiding all liability of clogging the machine, and the forks yet being free to spring back when they come in contact with any obstacle. Also in combining a rake with the tedder in such a manner that one balances the other, and either may be used without the other interfering with its operation.

To enable others skilled in the art to make and use my invention, I will proceed to describe its construction and operation.

I construct my tedder, with wheels and shafts, in the usual manner. The tedder is supported by the arms A A, which are pivoted to the shaft S by the pivot i. The rake is supported by the arms B B, and is pivoted to the shaft by the pivot z; the arms B and A are connected together by the arm J, as seen in figs. 2 and 7, in such a manner that when the tedder is lowered into its working position the rake is elevated out of the way, and when the rake is lowered the tedder will be elevated out of the way; the rake balancing the tedder all the while through the combination of the arms B, J, and A, shown in fig. 7. The pinion P cogs into gears on the drying-wheel W, when the tedder is in position to work, as seen in fig. 2. The pinion P is placed on the end of a shaft, L, which runs through the dead-centre U, as seen in fig. 4, not in the middle of the dead-centre, but on one side of its centre. The pinion-shaft L extends through the entire length of the cylinder, a little on one side of the centre on which the cylinder C revolves, which is shown in figs. 3 and 4, 12 and 13. The heads b b revolve on the dead-centre U, which is made large enough to enclose the pinion-shaft L, shown in figs. 4 and 13. The dead-centre U is attached firmly to the arm A. The pinion-shaft L is provided with an internal gear-wheel, F, which cogs into the gear-wheel V, which is placed in the centre of the cylinder C, and is connected

to it by the disk. The gear-wheel V has a hole through it as large as the dead-centre U, on which it turns, so that it may revolve without interfering with the shaft L, which passes through it on one side of its centre, figs. 3, 4, and 13. It is well-known that the rapid rotary motion of the forks in hay-tedders, when in operation, is very destructive to the forks if they come in contact with any obstacle that will not yield readily. Obstacles that a hay-rake would pass without any damage to the rake-teeth will badly injure or break the forks of a hay-tedder; and in order to make a hay-tedder practicable the forks must be constructed in such a manner that they can be readily replaced at small expense. The forks of this machine may be constructed with both tines made of one rod; but when made in this manner they must be constructed with a short bend which forms the loop that connects the two tines; but this mode of construction is objectionable, as the short bend which forms the connection or loop between the tines is very liable to break in bending, or so weaken the wire that it is liable to break in use; and if one tine becomes injured the entire fork must be removed, which it is difficult to do. To avoid the above difficulties I construct the two tines of the fork of separate pieces, and connect their shanks with the block h which is made with holes to receive them. The forks f f are coiled around the tube c c, seen in figs. 5 and 6, which is attached to the shaft a by the arms g g. The shanks of the forks are held in place by the block h on the shaft a, though which block they pass, see figs. 5 and 6, 10 and 11. The shaft a is held in position by the revolving-heads b b, fig. 12. The connecting-arm D extends from and attaches to the tube c c, (around which the forks are coiled,) and to the pinion-shaft L, seen figs. 11 and 5. The arm D may be connected to the shank of the fork, and the coil may be connected to the revolving-heads; but if so arranged the force exerted to operate the forks is transmitted by the connecting-arm to the shank, thus, indirectly to the forks, causing a heavy strain on the shank and coil of the forks, and increasing the friction. When the forks are connected as above the shaft is placed above the centre of the revolving-heads, shown in figs. 8 and 10; but if arranged, as shown in fig. 5, the arm D is connected with the coil of the forks, and the force to operate the forks acts directly upon them and does not strain the shank or the coil, shown in figs. 9 and 11. The forks are placed spirally around on the rotating-heads, and by the shafts a a each head is connected with the next, and thus all the heads are attached and revolve together. These heads may be covered by lags, thus forming a cylinder and protecting the internal parts from the weather and liability to accidents; but will be equally effectual in its operation if left open as a skeleton, shown in fig. 12. The tedder may be constructed with the shafts a a extending through its entire length, and employing only the two end heads, but this would require that the shafts should be quite stout and heavy, or they would spring when in operation. If a less number of shafts than forks is used the forks must be set in rows, thus more than one fork acting at a time, which is objectionable; for instance, if four shafts and eight forks are employed, it will be seen that two forks must act at a time, thus throwing the hay in bunches. But if the forks are set spirally around the shaft L, as shown in fig. 12, the total length of all the shafts employed to hang the forks will be but little more than the length of the tedder, thus but one fork will act at a time, and the machine can be manufactured at less expense. Each fork and shaft being independent, any one may be removed for repairs without disturbing any other part of the machine. O is a lever to operate the rake, and raise and lower the tedder. d is an arc on which the handle O is held in place by the pins r r'. The arm A is constructed with projections which form a dead-centre, upon which the head revolves, (see fig. 4,) and which serves as a box in which the shaft L turns.

Operation.

When the tedder is lowered into position to work, as shown in fig. 2, the pinion P is in cog with the internal gear on the driving-wheel W. When the team starts with this machine the wheel W rolls along the ground, and the pinion P and shaft L are driven around rapidly. The internal gear-wheel F, fig. 4, is firmly fixed on to the pinion-shaft L, and as it turns it causes the gear-wheel V, into which it cogs, to revolve still more rapidly. As the gear-wheel V is placed in the centre of the revolving-head b the cylinder is made to revolve by being attached to the revolving-heads b, on which the gear V is firmly fixed. Thus the heads b b are made to revolve on the dead-centre U, the pinion-shaft L passing through the tedder on one side of its centre, so that the shafts a a approach and recede from the shaft L as they revolve round it, (shown figs. 4, 12, and 13.)

The forks f f are coiled around the tube c c which swings on the shaft a by the arms g g. When the cylinder is in the position shown in fig. 5, by the full lines, with the forks f f at the bottom of the rotating-heads b b, the shaft a, between the heads, is brought near to the pinion-shaft L, and the connecting-arm D forces the tube c c down towards the outside of the shaft a, so that the forks stand in the position as shown. Now, as the heads revolve, the forks f f throw the hay before them with a quick, accelerated motion in addition to their rotary motion, and the impulse given to the hay by the accelerated motion of the forks tosses the hay off, and as the heads revolve the shaft a recedes from the shaft L, with which it is connected by the arm D, causing the forks to rock back and pass up with a retarded motion entirely free from hay. Thus a positive accelerated motion is given to the forks, in addition to their rotary motion, during the first part of their revolution while they act on the hay, and a retarded or backward motion during the latter part of their revolution, thus avoiding all liability to clog the machine, and the hay is effectually shaken up with a motion similar to that of the hand-fork. The position of the forks, as above described, is shown in figs. 9 and 11.

When the arm D is connected to the shank of the fork as shown in figs. 8 and 10, the shaft L must be placed in the dead-centre above the centre of the revolving-heads, and the motion of the forks will be the same as above described; but by this arrangement there will be a greater strain on the shank and coil of the forks, and by thus increasing the friction it will require more force to drive the machine. The coil in the forks forms a spring, which will yield when the forks come in contact with any obstacle.

By the arrangement of the tube c c, arm g, and block h, the coil of the fork can be made to rest on the

tube *c*, which always maintains the same relative position to the forks *f f*, thus avoiding all friction and wear on the coils, which would be caused if the forks rocked on a pivot or shaft passing directly through the coil of the fork, which wear would soon weaken and destroy the strength of the coil at a point where the greatest power is exerted in operating upon the hay. The block *h* is connected to the rotating-heads by the shaft *a*, on which it swings. The shanks of the forks passing through the block *h* connect the forks to the rotating-heads.

By the above arrangement, the single tines of the forks are firmly attached together; but either of them can be readily removed and replaced when injured, by drawing out the short shaft *a*, which simply holds one fork, thus saving the expense of a whole fork when one tine only is injured.

By placing the forks spirally around on the rotating heads, one fork only acts upon the hay at a time, thus shaking up the hay in single forkfuls, and not in large bunches, as would be the case if two or more forks acted at a time.

The rake *R* and the tedder are hung by the arms *B J* and *A*, as described in the construction, in such a manner that one balances the other, and either may be raised out of the way while the other is at work.

In fig. 7 the tedder is represented as down in its working position, with the rake elevated, by the full lines, and the dotted lines represent the rake as down in working position, with the tedder elevated.

When the tedder is elevated, the pinion *P* is not in cog with the gear on the wheel *W*, as the pinion and cylinder *C* swing by the arms *A A*, which are pivoted by the pivot *i* at a sufficient distance from the centre of the wheel *W* to throw the pinion *P* out of gear as it is elevated.

When the rake has been lowered, and is filled with hay, and the operator wishes to discharge the hay, he pulls the top of the bent lever *O O* back, pushing the arm *T* down, which forces the curved arm *A* down; but as the arm *A* falls, it draws down the end of the lever *B*, to which it is attached by the arm *J*. As the end of the arm *B*, which is attached to the arm *J* is lowered, the other end, to which the rake *R* is attached, is elevated as the arm *B* turns on the pivot *z*, and the hay is discharged behind the tedder from the rake. The tedder now being in gear while the rake is elevated, throws the hay back from under it on to the windrow formed by the rake, thus making an opening in the hay close to the windrow, into which opening the rake is lowered after it has passed over the windrow. By this arrangement all scatterings after the rake, where it divides the hay from the windrow, are avoided. When the rake is elevated the tedder is in its working position, and spreads the hay and shakes it up without any interference whatever from the rake.

The handle *O O* is held in its position by the pins *r r'*, so that the rake or tedder may be held in position to operate as described.

The gears *F* and *V* are placed inside of the head or disk *Q*, to secure them from being clogged with hay while in operation, (see fig. 4.)

By means of the arms *A A* and the lever *O O*, the driver in his seat may throw the tedder in and out of gear, or elevate it sufficiently to pass from field to field.

What I claim as my invention, and desire to secure by Letters Patent, is—

1. The forks *f* when so operated as to revolve around a common centre, and at the same time to have an oscillatory motion communicated to them by the positive action of mechanism by which their points shall be thrown forward with an accelerated motion when acting upon the hay, and be retracted when throwing off the hay, substantially in the manner set forth.
2. So arranging the revolving shaft *L* that it shall pass eccentrically through the dead-centre *U*, and, receiving motion from the wheel *W* through the pinion *P*, shall communicate it to the forks *f*, substantially in the manner set forth.
3. The combination of the shaft *L* placed eccentrically to the centre of the rotating heads *b* with the arms *D*, shaft *a*, and forks *f*, substantially as and for the purpose set forth.
4. The balancing of the tedder by the rake, substantially as described.

GEORGE E. BURT.
